UNITED STATES PATENT OFFICE

HERMANN KLOPPE, OF CHARLOTTENBURG, GERMANY

ILLUMINATED FOUNTAIN

Application filed June 11, 1925, Serial No. 36,416, and in Germany June 12, 1924.

My invention relates to improvements in illuminated fountains, and more particularly in fountains of the type in which light of different colors is thrown into the jets of water. 5 The object of the improvements is to provide a fountain of this type by means of which a great variation of the color effects can be produced, and with this object in view my invention consists in providing a plurality of 10 multi-color filters one behind the other in the direction of the light falling into the jets of water, and providing means for shifting the said color filters relatively to each other so as to set fields of varying colors one behind the 15 other in the path of the light rays. Preferably one of the said filters is provided with fields having comparatively deep colors, while the other one, which is designed for varying the light passing through the first-named filter, has fields of comparatively light colors, so that the brilliancy of the light passing 20 through both filters is not reduced as much as when the field colors in both filters are comparatively deep. 25 Another object of the improvements is to provide a fountain which is provided with a refractive rim constructed so as to collect the jets of water falling downwardly into the basin, and further to refract the light emanating 30 from the water of the fountain collected within the basin, which water is likewise colored by the light passing through the color filters. Preferably the said rim of transparent material consists of glass having depressions or projections cut or pressed thereon, 35 which projections or depressions refract or disperse the successive colored rays emanating from the water and have a beautiful illuminating effect. The rim of glass, which collects the water falling from the fountain, prevents spoiling of the decorative mounting 40 of the fountain by the drops of water. The said glass rim may be made integral with the basin of the fountain. 45 For the purpose of explaining the invention an example embodying the same has been shown in the accompanying drawing, in which the same reference characters have been used in all the views to indicate corresponding parts. In said drawing,

Fig. 1 is an elevation showing the fountain,
Fig. 2 is a top-plan view,

Fig. 3 is a section on an enlarged scale of the rim surrounding the fountain,

Fig. 4 is a partial sectional elevation on an 55 enlarged scale showing the said rim and the basin,

Fig. 5 is a sectional elevation showing the top part of the fountain, and

Figs. 6 and 7 are top-plan views showing 60 the color filters.

In the example shown in the figures the fountain comprises a basin 9 supported on legs 10, an axial pipe 11 for the supply of water under pressure and having a nozzle 12 at its top, a source of light represented in Fig. 5 by two incandescent electric lamps 13, and color filters 14 and 15. The bottom of the basin 9 is provided with two panes 16 of transparent material, which panes are located above the 65 lamps 13 and the color filters 14 and 15. The color filters 14 and 15 are adapted to be rotated relatively to each other. As shown the lower filter 14 is connected with a gear wheel 17 engaged by a pinion 18, said pinion being 70 provided with suitable means for imparting intermittent or continuous movement to the filter 14. In a similar way the filter 15 is connected with a gear wheel 19 engaged by a pinion 20, which is likewise connected with a suitable driving mechanism. The pinions 18 and 20 are operated so as to shift the filters 14 and 15 relatively to each other and successively to place different fields of the filters into position 75 below the transparent panes 16. 80

In Fig. 6 I have shown a plan view of the upper filter 15. As shown the said filter is divided into sectors of different colors, the said colors being for example green, blue, red, orange, white, green, blue, red, orange and white. In Fig. 7 I have shown a plan view of the filter 14, which filter is divided into sectors having comparatively light colors. As shown the successive sectors have the following light color tints: On the top of the basin 85 therein a rim 22 of transparent material such as glass having depressions or projections 23 cut or pressed therein. Preferably the said rim is slightly conical in form. 90

The operation of the fountain is as follows: Water under pressure is supplied through the pipe 11 and the nozzle 12, the said water issuing from the nozzle 12 in the form of jets. 5 The lamps 13, 13 are illuminated, and the light from the said lamps is directed upwardly through the color filters 14, 15, the transparent panes 16, the water confined within the basin 9 and into the jets of water produced by the nozzle 12. Thus the jets and drops of water are illuminated, and further, the colored light rays passing through the water and impinging on the rim 22 are refracted, thus producing a beautiful color effect around the 10 fountain. By rotating the filters 14 and 15 at different velocities or in opposite directions continuously new combinations of color fields of the filters are moved into the paths of the lamps 13, 13, so that a great variety of the 15 light effects is produced.

While in describing the invention reference has been made to a particular example embodying the same I wish it to be understood that my invention is not limited to the construction shown in the drawing, and that various changes may be made in the general arrangement of the apparatus and the construction of its parts without departing from the 20 invention.

30 I claim:

1. A basin for a fountain comprising a bottom having spaced parts permitting the passage of light arranged about a central point of the basin, said bottom having other parts 35 through which the passage of light is prevented, said spaced parts permitting the passage of light however being adapted to prevent the passage of water therethrough.

2. A basin for a fountain comprising a bottom having a plurality of light transmitting sectors separated by sectors through which the passage of light is prevented, said sectors being arranged about a central point of said basin and said light transmitting sectors 40 being impassable by water.

3. A fountain comprising a basin having a plurality of light transmitting sectors separated by sectors through which the passage of light is impeded, said sectors being arranged about a central point of said basin and said light transmitting sectors being impassable by water, means for dispersing a liquid above said sectors, means illuminating said light transmitting sectors from below and means for varying the color of the illumination.

4. A fountain comprising in combination a basin having lateral portions of its bottom at intervals adapted to transmit light but to impede the passage of water, means for dispersing a liquid above said basin and said lateral portions, means for producing light to be passed from below said basin through 55 said portions adapted to transmit light, and

means for varying the color of the light from said light producing means.

5. A fountain comprising in combination a basin having lateral portions of its bottom at intervals adapted to transmit light but to impede the passage of water, means for dispersing a liquid above the bottom of the basin and also above said lateral portions, means for producing light to be passed from below said basin through said portions adapted to transmit light, light filters having various color sections in the path of the light from said light producing means and means for causing relative motion of said filters. 70

6. In combination in a fountain, a basin, 80 means for illuminating the interior of said basin, a light refractor arranged about the edges of said basin and extending above the same, the said light refractor being open at its top and bottom to permit the free elevation and return of water therethrough and having refracting portions inclined towards the center of said basin.

7. In combination in a fountain, a basin, 85 means for illuminating the interior of said basin and the space above said basin, conical means for producing dispersion of light, said conical means having an open bottom, the edges of its open bottom being positioned near the edges of the basin and its inclined 90 walls leaning towards the center of the basin and extending above the edges of the basin.

8. A basin having means for illuminating the interior thereof in combination with means adapted to produce dispersion of light 100 arranged about the basin and rising above the edge thereof.

9. In combination with a basin of a luminous fountain, means for producing dispersion of light arranged about the basin near 105 the edge thereof and inclined towards the center of the basin.

In testimony whereof I hereunto affix my signature.

HERMANN KLOPPE.
